UNITED STATES PATENT OFFICE

143,382

DESIGN FOR A FAUCET HANDLE OR THE LIKE

Roy H. Zinkil, Oak Park, Ill., and Henry Dreyfuss,
New York, N. Y., assignors to Crane Co.,
Chicago, Ill., a corporation of Illinois

Application April 26, 1945, Serial No. 119,239

Term of patent 14 years

(Cl. D91—3)

To all whom it may concern:

Be it known that we, Roy H. Zinkil and Henry Dreyfuss, citizens of the United States, residing at Oak Park and New York, in the counties of Cook and New York, and States of Illinois and New York, respectively, have invented a new, original, and ornamental Design for a Faucet Handle or the Like, of which the following is a specification, reference being had to the accompanying drawing, forming part thereof.

Fig. 1 is a plan view of the faucet handle embodying our design.

Fig. 2 is a side view thereof.

Fig. 3 is a front view thereof.

We claim:

The ornamental design for a faucet handle or the like, substantially as shown.

ROY H. ZINKIL.
HENRY DREYFUSS.
